Primary Examiner — Elizabeth Albert(74) *Attorney, Agent, or Firm* — Fish & Richardson P.C.(57) **CLAIM**

The ornamental design for a bulletin board with compartment for computer, substantially as shown and described.

DESCRIPTION

FIG. 1 is a perspective view of a bulletin board with compartment for computer showing our new design.

FIG. 2 is a front elevation view thereof.

FIG. 3 is a left side elevation view thereof.

FIG. 4 is a right side elevation view thereof.

FIG. 5 is a top plan view thereof.

FIG. 6 is a bottom plan view thereof; and,

FIG. 7 is a second perspective view thereof shown at a different angle than in FIG. 1.

1 Claim, 6 Drawing Sheets(56)
